UNITED STATES PATENT OFFICE.

ARCHIBALD H. CROZIER, OF OSWEGO, NEW YORK.

MACHINE FOR CREEASING AND BEVELING BARRELS.

Specification of Letters Patent No. 11,211, dated July 4, 1854.

To all whom it may concern:

Be it known that I, ARCHIBALD H. CROZIER, of Oswego, in the county of Oswego and State of New York, have invented a new and useful Improved Machine for Beveling and Creasing Barrels; and I do hereby declare that the following is a full, clear, and exact description of the construction and operation of the same, reference being had to the annexed drawings, making a part of this specification, in which—

Figure 1, is a front elevation of my improved machine. Fig. 2, is a detached view of a cam, which operates the platform on which the barrel is placed. Fig. 3, is a plan or top view of the cutters and mechanism by which they are operated. Fig. 4, is a detached perspective view of the cutters.

Similar letters of reference indicate corresponding parts in the several figures.

This invention relates to a new and improved machine for beveling the ends of barrels, and cutting the creases therein to receive the heads, and consists in the employment or use of a movable platform, and movable cutters arranged and operating as will be fully shown hereafter.

To enable others skilled in the art to make and use my invention, I will proceed to describe its construction and operation.

A, Fig. 1, represents a frame constructed in any proper manner, to support the several working parts of the machine.

B, is a platform at the lower end of the frame, A. This platform works, or is fitted between guides, (a), (a), attached to the inner sides of uprights, (b), (b), of the frame.

C, C, are rods attached, one to each end of the platform, and extending upward through the cross piece, (c), of the frame, and attached to the ends of a bar, D, which bar rests upon an elliptic spring, E, on the upper surface of the cross piece, C.

F, is a cam which bears against the bar, D, said bar being hung at the end of a shaft, G, having its bearings on the upper parts of the uprights, (d), (d), which are attached to the cross piece, (c). At the end of the shaft, G, opposite to the end in which the cam, F, is hung, there is a worm wheel, H, into which a screw, I, gears, said screw being at the upper end of an upright shaft, J. At the lower end of the shaft, J, there is a bevel pinion, (e), which gears into a bevel pinion, (f), on a horizontal shaft, K.

On the outer end of the shaft, K, there is a crank, L, and on the opposite end there is a bevel pinion, (g), which gears into a bevel pinion, (h), on an upright shaft, M.

The shaft M, has attached to its lower end, a horizontal plate N, see Fig. 3, in one end of which a rectangular recess (i), is made, to receive a cutter stock (j), shown in Figs. 3, and 4. The stock (j), has arms or rods (k), (k), attached to it by pivots, and the outer ends of these arms are attached to the sides of a worm wheel O, at a certain distance from its center, see Figs. 1 and 3.

The worm wheel O, works in bearings attached to the plate N, and gears into a stationary screw P, through which the shaft M, passes.

The stock (j), has two cutters (l), (m), attached to it, shown clearly in Figs. 3 and 4. The cutter (l), is upright, and somewhat inclined or bent at its upper end, as shown in Figs 1 and 4. The cutter (m), is horizontal, and of gouge form.

Q, is a circular horizontal band or rim, attached to hangers R, R, which are secured to a cross piece (n), of the frame, see Fig. 1. The band or rim Q, encompasses the plate N, see Figs. 1 and 3.

Operation. The barrel to be operated upon is placed upon the platform B, see Fig. 1, the barrel being represented by S; and motion is communicated to the shaft K, by turning the crank L, or in any other manner.

As the shaft K, rotates, a rotary motion is communicated to the shaft M, and plate N, by means of the bevel wheels (g), (h), and the cam F, is also made to rotate by means of the shaft J, which communicates motion to the shaft G, from the shaft K.

As the shaft M, rotates, the cutters (l), (m), have a horizontal reciprocating motion given them by means of the stationary screw P, which causes the worm wheel O, to rotate, and a vertical reciprocating motion is given the platform B, by means of the cam F, and spring E.

When the platform B, is depressed, the barrel S, is placed upon the platform, sufficient time being allowed for this, owing to the shape of the cam, the most prominent portion of which, from v to v, see Fig. 2, is part of a circle, when the prominent part of the cam has passed the bar D, the platform B, and consequently the barrel S, is raised by the action of the spring E, and the upper end of the barrel fits snugly within the band or

rim *Q*, and the cutter stock (*j*), and cutters (*l*), (*m*), move outward from the plate *N*, and the cutter (*l*), trims evenly the top 5 of the barrel, and forms the necessary bevel thereon, and the cutter (*m*), forms the crease to receive the head. When this is accomplished, the prominent portion of the cam begins to act upon the bar *D*, and depresses the platform, and the cutters move 10 inward, owing to the attachment of the arms or rods, (*k*), (*k*), to the worm wheel *O*, which is in effect a crank motion. The cutters commence moving inward a short time before the barrel commences moving 15 downward, in order to allow the cutter (*m*), to clear the crease. This is effected by properly placing the cam upon the shaft *G*,

and having a proper relative position between the cam and the crank attachment of the arms (*k*), (*k*), to the worm wheel *O*. 20

What I claim as new, and desire to secure by Letters Patent, is:—

The movable platform *B*, and movable cutters (*l*) (*m*), arranged substantially as herein shown and described, so that the 25 cutters may be moved from the barrel, and free from the crease when the platform and barrel descend, and moved toward the barrel when the platform and barrel are raised.

ARCHIBALD H. CROZIER.
